United States Patent Office

Des. 182,995
Patented June 10, 1958

182,995

TWIN SOFA BED AND TABLE UNIT

Louis Elliott Frey, Los Angeles, Calif.

Application November 19, 1956, Serial No. 43,801

Term of patent 14 years

(Cl. D5—4)

Fig. 1.

Fig. 2.

Fig. 1 is a perspective view showing a twin sofa bed and table unit embodying my new design in closed position;

Fig. 2 is a perspective view of the same in open position.

The dominant features of the design are shown in solid lines.

I claim:

The ornamental design for a twin sofa bed and table unit, substantially as shown and described.
